(57) **CLAIM**

The ornamental design for a toothbrush sanitizer, substantially as shown and described.

DESCRIPTION

FIG. 1 is a front right quarter perspective view of the toothbrush sanitizer of the present invention. The power switch in dashed lines is expressly disclaimed.

FIG. 2 is a rear left quarter perspective view of the toothbrush sanitizer of the present invention. The power plug in dashed lines is expressly disclaimed.

FIG. 3 is a top view of the toothbrush sanitizer of the present invention.

FIG. 4 is a bottom view of the toothbrush sanitizer of the present invention.

FIG. 5 is a front elevational view of the toothbrush sanitizer of the present invention. The power switch in dashed lines is expressly disclaimed.

FIG. 6 is a rear elevational view of the toothbrush sanitizer of the present invention. The power plug switch in dashed lines is expressly disclaimed.

FIG. 7 is a right side elevational view of the toothbrush sanitizer of the present invention. The power plug and power switch in dashed lines is expressly disclaimed.

FIG. 8 is a left side elevational view of the toothbrush sanitizer of the present invention. The power plug and power switch in dashed lines is expressly disclaimed; and,

FIG. 9 is a fifth right quarter perspective view of the toothbrush sanitizer of the present invention illustrating the apparatus in its intended field of use. The toothbrush handles and power switch in dashed lines is expressly disclaimed.
